CLAIM

The ornamental design for a sandal as shown and described.

DESCRIPTION

FIG. 1 is a right perspective view of a sandal, showing my new design;

FIG. 2 is a left perspective view thereof;

FIG. 3 is a top side view thereof;

FIG. 4 is a partial enlarged view of FIG. 1; and,

FIG. 5 is a partial enlarged view of FIG. 2.

The broken lines in the figures are for the purposes of illustrating portions of the sandal, which form no part of the
